UNITED STATES PATENT OFFICE.

MILLARD FILMORE RICHARDS, OF TOLEDO, OHIO.

TAG-HOLDER.

SPECIFICATION forming part of Letters Patent No. 371,629, dated October 18, 1887.

Application filed July 21, 1887. Serial No. 244,934. (No model.)

To all whom it may concern:

Be it known that I, MILLARD FILMORE RICHARDS, a citizen of the United States, residing at Toledo, in the county of Lucas and State of Ohio, have invented certain new and useful Improvements in a Tag-Holder; and I do hereby declare that the following is a full, clear, and exact description of the invention, which will enable others skilled in the art to which it appertains to make and use the same, reference being had to the accompanying drawings, and to the letters of reference marked thereon, which form part of this specification.

15 My invention relates to tag-holders, and has for its object to provide a holder that can be cheaply manufactured, as well as convenient in operation, that shall hold the tag away from the goods, and that will not catch into the folds 20 of the same.

25 My invention consists of a tag-holder formed of a single piece of wire bent into such shape that it will readily grasp a fold of fabric, so as to hold thereon firmly and display a tag at a distance from the end of the roll of goods.

In the drawings, Figure 1 is a top plan view. Fig. 2 is a side view showing the clasping jaws closed. Fig. 3 is a similar view showing the clamping-jaws opened. Fig. 4 is a bottom 30 plan view.

Similar letters of reference indicate similar parts in all the views.

35 A is the tag-holder, composed of a single piece of wire bent at one end to form a circular clamping-frame, B, whose center coacts with a pin, C, bent at an acute angle to a clamping-jaw, D, in parallel relation thereto.

From the circular frame B the wire extends tangentially and to a point intermediate the 40 length of the complete device, and is there bent at a right angle to a distance corresponding to the diameter of frame B, forming a transverse portion, E, and is then bent at right angles to the portion E, from which point it extends in a parallel line with the front portion to the end, where, by again bending at a right angle to the side and again bending at a right angle to the transverse end portion, F, the wire is directed toward the 45 frame B.

50 At a point intermediate the transverse portions E and F there is formed a circular frame, G, which serves the double purpose of hold-

ing the tag H away from the roll, and also as a finger-rest when applying tension to the 55 frame in opening the clamping-jaws.

From the transverse end F the wire extends toward frame B to a point directly over and within the transverse portion E, where it is bent at a right angle and extended below the 60 bottom wire, where it is again bent at a right angle and extended in parallel relation to the front portion, terminating at a point central to frame B, thereby forming clamping-jaw D, where the point is bent at an acute angle and 65 pointed to form pin C, which point is sharpened in severing from the main wire by being cut upon an incline.

In operation, when it is desired to suspend a tag from a roll of goods, it is threaded upon 70 the holder, as shown in Fig. 2. The clamping-jaws are opened, as shown in Fig. 3, by resting frame G upon the finger and pressing upon clamping-jaw D. The fold of goods is then inserted, and the tension of the wire causes the 75 frame B and pin C to grasp the same and retain the holder in the desired position.

It will be seen that frame G serves an important purpose, since by its surface it not only assists in opening the holder, but prevents its rolling or turning sidewise between the thumb and finger during this operation, as well as serving to keep the tag from sliding 80 within the folds of cloth.

Having described my invention, what I 85 claim, and desire to secure by Letters Patent, is—

The herein described tag-holder, formed of a single piece of wire and comprising a pointed hook or pin member and a protecting-ring 90 member, the pin member bent into a vertical rectangular spring-frame adapted to hold a tag and to release the pin, and its opposite free end terminating in a right-angled pin or hook, and the other or ring member provided 95 with a laterally-extended frame having an intermediate spring-coil, said member terminating in a protecting-ring, substantially as described.

In testimony that I claim the foregoing as 100 my own I hereby affix my signature in presence of two witnesses.

MILLARD FILMORE RICHARDS.
